UNITED STATES PATENT OFFICE.

RUDOLF JOH. WILH. REINHARD, OF HAMBURG, GERMANY.

BURNER FOR GAS-LAMPS.

SPECIFICATION forming part of Letters Patent No. 643,006, dated February 6, 1900.

Application filed May 11, 1899. Serial No. 716,458. (No model.)

To all whom it may concern:

Be it known that I, RUDOLF JOH. WILH. REINHARD, manufacturer of metal goods, a subject of the Emperor of Germany, residing at Hühnerposten 23, Hamburg, in the Empire of Germany, have invented certain new and useful Improvements in and Relating to the Burners of Gas-Lamps, of which the following is a full, clear, and exact description.

This invention relates to a device applicable to street gas-lamps having double burners the jets of which are ignited by means of separate igniting-jets.

The object of this device is to enable the said igniting-jets to be extinguished while the main jets are burning.

This invention is illustrated in the annexed drawings.

Figure 1 shows in central sectional elevation a double-burner street-lamp provided with this device. Fig. 2 is a side elevation of Fig. 1 in section on the line uu , Fig. 1. Fig. 3 is a front elevation of the body containing the regulating slide-valve in front end view, the lid being removed. Fig. 4 is a rear elevation of the same, likewise with the lid removed. Figs. 5 to 8 show the various positions of the rotary valve. Figs. 9, 10, and 11 are crossed sections through the burner-carrier on the lines xx , yy , and zz of Fig. 1.

According to this invention the essential part of the apparatus as illustrated consists in the slide-valve body A, which contains the rotary slide-valve B. The body A is divided by a vertical wall a , on the front side of which, Fig. 3, there are arranged chambers I II III IV, which communicate at the top by means of holes i^2 i^3 with the pipes o^2 o^3 , that convey the gas to the main jets, and by means of holes i' i^4 with the pipes o' o^4 , that convey the gas to the igniting-jets. Each of the chambers is connected by means of a hole (chamber I is connected by two holes) with the space m behind the wall a , into which the gas enters in the direction of the arrow, Fig. 2, and in which the slide B is situated and bears firmly against the wall a . The pin b of the slide is led forward through the lid a' of the chambers I to IV, and there it is provided with a handle b^2 . Upon the back of the slide B there acts a spring b^3 , that is held by means of a cover m' , which closes in the space m and in which there is

also situated a cleaning-screw m^2 . The slide is formed with a gap s , and according as this gap is moved in front of the holes which are 55 formed in the wall a and which lead the gas to the chambers I to IV the gas passes into the pipes o' o^2 o^3 o^4 and to the jets.

In the position shown in Fig. 4 the gas passes out of the chambers I to IV to the right 60 and to the left hand through i' o' and i^4 o^4 to the two igniting-jets. The main jets are extinguished. In the position shown in Fig. 5 gas still passes to the right hand through i^4 o^4 to the igniting-jet and now also to the 65 main jet on the left through i^3 o^3 . The igniting-jet on the left is extinguished. If the slide is further rotated out of the position Fig. 5, then in the position Fig. 6, the passage i^2 o^2 to the main jet on the right is 70 opened; but the passage i^4 o^4 from chamber IV to the igniting-jet on the right is also still open, so that the main jet can be ignited thereby, and then only after the slide has been rotated into the position Fig. 7 the igniting-jet on the right is extinguished, and now 75 both main jets are burning. In the position Fig. 8 the main jet on the right, which is fed through the passage i^2 o^2 , is burning, while the passage i^3 o^3 to the main jet on the left 80 has been shut after the passage i' o' to the igniting-flame has been opened and the latter has been ignited by its own main jet. By reason of the arrangement of the rotary slide it is rendered possible to arrange the several 85 passages (the holes which open from the gas-space m through the wall a into the chambers I to IV) at relatively great distances from one another, so that in adjusting the slide-handle by hand large differences can occur at times 90 without such differences interfering with the desired supply of gas to the jets. The passages will even then be always connected up together in the desired way, even though there be a certain amount of play in the setting or adjustment of the handle.

What I claim, and desire to secure by Letters Patent, is—

The combination of the main jets, the igniter-jets, the separate passages leading to the main and igniting jets each communicating with one of a series of annular gas-chambers separated from the main gas-supply by a partition but each communicating with the

main gas-supply by an aperture in said partition; with a rotary valve in said main gas-chamber provided with a segmental slot whereby the supply to the main jets may be
5 cut off when the igniter-jets are burning and vice versa, and the main jets may be made to burn singly or together.

In witness whereof I subscribe my signature in presence of two witnesses.

RUD. JOH. WILH. REINHARD.
